(57) **CLAIM**

The ornamental design for a spice mill as shown and described.

DESCRIPTION

FIG. 1 is a top isometric view of a spice mill showing our new design.

FIG. 2 is a bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The dashed lines in the drawings indicate portions of the spice mill which form no part of the claimed design. The surface shading is provided to illustrate a contrast between materials of the claimed design. While the surface shading forms no part of the claimed design, the contrast between the materials forms a part of the claimed design.
